(57) **CLAIM**

The ornamental design for a display screen of a communications terminal with a graphical user interface with drop down box, as shown and described.

DESCRIPTION

FIG. 1 is a front view of first embodiment of a display screen of a communications terminal with a graphical user interface with drop down box design;

FIG. 2 is a front view of a second embodiment thereof;

FIG. 3 is a front view of a third embodiment thereof;

FIG. 4 is front view of a fourth embodiment thereof; and,

FIG. 5 is a front view of a fifth embodiment thereof.

The broken line showing of a portion of a display screen is included for the purpose of illustrating portions of the article and forms no part of the claimed design.

1 Claim, 5 Drawing Sheets
